SORTER POCKET AND CHUTE BLADE CONSTRUCTION

Filed May 3, 1947

FIG. 2.

UNITED STATES PATENT OFFICE

2,461,418

SORTER POCKET AND CHUTE BLADE
CONSTRUCTION

Eugene A. Ford, Endicott, N. Y., assignor to International Business Machines Corporation, New York, N. Y., a corporation of New York

Application May 3, 1947, Serial No. 745,833

4 Claims. (Cl. 271—64)

1

The present invention relates to sorting machines and, more particularly, to a card receiving pocket construction which, although it is capable of use in connection with a wide variety of sorting machines, is particularly well adapted for use in multiple deck sorting machines where space limitations are a matter of concern. Multiple deck sorting machines are broadly of two types. In both types, two or more sets of card receiving pockets are arranged in superimposed relationship with the pockets of each set being arranged in alignment so as to extend longitudinally of the machine. The pockets of each set are completely exposed on the same side of the machine, thus enabling a single operator to attend to the removal of cards from the various pockets and do all other necessary functions contingent upon proper operation and care of the machine with a minimum amount of lost motion.

In one type of multiple deck machine, the various superimposed sets of pockets are each served from a respective card stack by an individual analyzing and distributing system, the cards issuing from the stack being conducted directly to the respective pockets to which they have been assigned by the analyzing and distributing system. Such a machine is shown in my copending application, Serial No. 748,426, filed May 16, 1947 for a Sorter. In other words, except for the matter of a common drive for the various analyzing and distributing systems and for impelling the cards through the machine at the various card levels, this type of machine is, for all intents and purposes, the consolidation in a single framework of a plurality of independent sorting machines.

In the other type of multiple deck sorting machine the various superimposed sets of pockets are collectively served from a single card stack by a single analyzing and distributing system, the cards proceeding to various card levels above the various sets of card receiving pockets and thereafter being directed to a particular pocket in one of the superimposed sets of pockets. Such a machine is shown in my copending application, Serial No. 745,835, filed May 3, 1947 now Patent No. 2,448,788 of September 7, 1948, for a Machine for sorting cards perforated in alphabetic code.

In either type of multiple deck sorting machine, all of the card levels or paths, except the uppermost card level, closely underlies the bottom of the next adjacent set of card receiving pockets, thereby rendering the cards at this level inaccessible to the operator in the event of a card

2

jam or other mechanical failure associated with the machine.

The present invention is concerned with a card receiving pocket construction having a bottom which is readily removable to afford access to the card level therebeneath and which is easily replaced by a simple snap action.

The provision of a pocket construction of the character set forth above being the principal object of the invention, another object thereof is to provide a pocket arrangement which is extremely simple in its construction and which may be constructed of light sheet metal stampings, thus materially reducing the cost of the same.

15 A still further object of the invention is to provide a card pocket construction in which the various individual pockets are substantially identical and are easily installed in a series relationship, thus further contributing toward economy of manufacture of the machine.

20 Yet another object of the invention is to provide an extremely simple and improved electrical card stop which is peculiarly well adapted for use in connection with the improved type of card receiving pockets.

25 Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a fragmentary side elevational view of a card receiving pocket constructed in accordance with the principles of the present invention showing the same installed in a sorting machine. This view also shows a portion of two adjacent card receiving pockets.

Fig. 2 is a top plan view of the structure shown in Fig. 1, certain parts being broken away to more clearly reveal the nature of the invention.

Fig. 3 is a sectional view taken substantially along the line 3—3 of Fig. 1 in the direction indicated by the arrows.

45 Fig. 4 is a sectional view taken substantially along the line 4—4 of Fig. 1 in the direction indicated by the arrows.

50 Fig. 5 is an enlarged detail side elevational view of one corner of the improved card receiving pocket.

55 Referring now to the drawings in detail and in particular to Fig. 1, this figure represents a central region of a multiple deck sorting machine and shows in side elevation a complete card receiving pocket, together with fragmentary por-

tions of adjacent card receiving pockets at the same level and also a fragmentary portion of one pocket in the level therebeneath. Only those portions of the sorting machine directly concerned with the installation of the card receiving pockets have been illustrated.

The sorting machine involves in its general organization a front plate 10 and a rear plate 12 and between these two plates there are installed two sets or series of card receiving pockets including an upper set designated in its entirety at 14 and a lower set designated in its entirety at 16. In the upper set, a single pocket is shown in side elevation with fragmentary portions of the next pocket to the left and the next pocket to the right also appearing in the view. In the lower set 16 a fragmentary portion of a single pocket appears.

An enlarged opening 18 is formed in the front plate 10 and to further identify this opening the upper edge thereof is indicated at 20 and the lower edge at 22. This opening spans the entire upper set of pockets 14. Similarly, an opening, the lower edge of which is identified at 24, spans the entire lower set of pockets 16. Both openings just described being formed on the same side of the machine, i. e., in the plate 10, an operator working on this side of the machine thus has convenient access to both sets of pockets and a minimum amount of lost motion is involved, while attending to the machine.

A plurality of upper card supports 26 extend across the machine from the front plate 10 to the rear plate 12 and are spaced along the machine at intervals and serve in part to support therebeneath the various upper card receiving pockets. These card supporting plates 26 have their upper edges at the same horizontal level and define among themselves an upper card line which has been so labeled in Fig. 1. A plurality of lower card supports 28, similar to the supports 26, define among themselves a lower card line, likewise labeled in this figure. Upper pairs of card impelling rolls 30 are associated with the card supports 26 and, similarly, lower card impelling rolls 32 are associated with the lower card supports 28.

The forward edges of each of the card supports 26 are beveled as at 27 to provide a card deflecting surface whereby the card advancing along the card line may be deflected downwardly into the respective pockets to which they have been assigned and for which they are intended. A plurality of relatively narrow chute blades 29 which may be formed of spring steel or the like are welded as at 31 to the upper surfaces of the supports 26 and extend forwardly of the machine from their respective supports. The chute blades 29 are of varying lengths, each terminating at its respective pocket and serving to guide the forward edges of the cards onto the deflecting surface 27 so that the cards may be deflected downwardly by the latter. The action of the deflecting surface 27 is supplemented, at each pocket by a deflecting blade 27a, which is sprung upward by the card feeding into the pocket and throws the rear edge of the card down, as soon as it is released by the feed rolls, thus causing the card to settle into the pocket with the correct side upward.

The upper card receiving pockets are suspended from and are in part supported by the card supports 26 and the lower card receiving pockets are likewise suspended from and partly supported from the card supports 28. The pockets of the upper series and of the lower series being identi-

cal, it is thought that a description of one will suffice for the other.

Each pair of card receiving pockets includes two pairs of depending sheet metal members or strips 34, the strips of each pair being arranged in parallelism and having their upper ends turned laterally and spot welded as at 36 or otherwise secured to the underneath surface of the card supports 26. The members 34 are curved in a region designated at 38 with a relatively large radius of curvature. In the extreme upper regions and in the extreme lower regions thereof the members 34 are substantially straight. Each pair of members 34 constitutes the forward restraining wall of one card receiving pocket and the rearward restraining wall of the next adjacent card receiving pocket. In other words, each pair of members 34 constitutes an open frame-like partition between adjacent card receiving pockets. The members 34 extend downwardly to a point adjacent the lower edge 22 of the opening 18 and their lower ends are turned laterally as at 39 and are clamped to the underneath side of a laterally extending supporting bar 40 which is generally of rectangular shape in cross section. Each of the bars 40 is supported solely from the rear plate 12 by means of a cap screw 42 which passes through a hole 44 formed in the rear plate 12 and which is threadedly received as at 46 in the squared supporting bar 40. The rear plate 12 and cap screws 42 form the sole supporting means for each of the bars 40. The forward ends of the bars 40 are spaced from the plane of the front plate 10.

The manner in which the laterally turned lower ends 39 of the members 34 are clamped to their respective supporting bars 40 is clearly illustrated in Fig. 5. Referring to this figure, and also Fig. 4, it will be seen that each bar 40 is provided with a pair of recesses 48 therein, which recesses communicate with a transverse bore 50 extending completely through the bar. A cap screw 52 having its head disposed in countersunk fashion in the recess 48 extends completely through the bore 50 and has its extreme end threadedly received as at 54 in a circular plate 56. The threaded portion or bore formed in the circular plate 56 is eccentrically disposed with respect to the plate, i. e., it is removed somewhat from the center of the circular plate and in assembling the various parts the major portion of the plate 56 projects in a forward direction relative to the card line and the extent of the plate 56 is such that it projects beyond the plane of the lower portion of its respective member 34, thus forming a ledge 58, the purpose of which will be set forth presently.

Each of the card receiving pockets is provided with a removable bottom plate designated in its entirety at 60. This bottom plate 60 is best illustrated in Figs. 1 and 4 and is formed of light, relatively thin, sheet metal. The plate is generally of rectangular configuration and has a rear edge region 62 adapted to rest upon the pair of supporting plates 56. The forward edge region 64 of the plate 60 is adapted to rest upon the top surface of one of the squared supporting bars 40. Each plate 60 is provided with a struckout tongue 66 which is curved as at 68 and which is adapted to be snapped into position in frictional engagement with the rear side of a respective supporting bar 40, as shown at the lower right-hand corner of Fig. 1. The tongue 66, when the plate 60 is in position in the pocket structure, frictionally bears against the side of the supporting bar 40 and maintains the plate 60 securely in its operative position. To install the plate 60, it is

merely necessary to place the rear edge 62 thereof in position on the shelf-like region or ledge 58 of the plates 56 and swing the plate 60 downwardly so that the curved portion 68 of the tongue 66 engages the side of one of the bars 40 and passes over a dead center position so that the plate 60 snaps into position and is securely held therein until such time as the operator chooses to remove the plate by a reversal of the installation process.

Various methods of installation of the pocket structure are possible but a preferred method consists in first positioning all of the transverse supporting bars 40 on the rear plate 12 of the sorting machine and tightening the cap screws 42 so as to render these supporting bars rigid. Thereafter, the laterally turned portions 36 of the members 34 may be spot welded in proper position on the underneath sides of the card supports 26. The cap screws 52 may then be passed through the bores 50 and through the laterally turned portions 39 of the members 34 and the plates 56 may then be threaded onto the lower ends of the cap screws 52. The plate 60 may then be assembled or installed at the lower ends of the various pockets in the manner previously described and the pocket structures are then complete and ready for card reception.

Referring now to Fig. 1, an electrical pocket stop which is designated in its entirety at 10 is secured within each pocket in the upper regions thereof on the concave side of the curved region 38 of one of the members 34. Obviously, this pocket stop may be placed on either one of the pair of members 34, but in the present invention, for purposes of illustration, the pocket stops are shown as being positioned on the front members of each pair, i. e., the members which are on the operator's side of the sorting machine.

Each pocket stop includes an insulating block 72 which is secured by a nut and bolt arrangement 74 to the member 34. A pair of contact arms 76 and 78 carry therebetween a pair of normally open contacts 80, the contact assembly being secured to and supported from the block 72 by means of the nut and bolt arrangement 74. The arms 76 and 78 are insulated from each other and also from the metallic member 34. The lower contact arm 78 is relatively long and its free end terminates adjacent the underneath side of the member 34. The contact arms 76 and 78 are provided with contact leads 82 which may be connected in any suitable manner to a relay mechanism, not shown, the purpose of which is to open the circuit leading to the sorting machine motor.

It will be seen that cards entering the card receiving pockets under the guiding action of the chute blades 29 will have their oncoming edges deflected downwardly by the inclined surface 27 of the card supports 26. The first oncoming card will thus fall into the pocket with its oncoming edge positioned downwardly. Because of the slight inclination of the bottom plate 60, the forward edge of the card will slide into position and occupy one corner of the pocket and the card will eventually lie flush with the inclined bottom plate 60 thereof. The cards will pile up within the pocket similarly oriented to form a stack until such time as the level of the lower or free end of the contact arm 78 of the pocket stop 10 is attained. The next oncoming card to be received in the pocket will seek a level above the level of the free end of the contact arm 78 and, because the width of the card is slightly greater than the distance from the free end of the arm

18 to the remote wall of the pocket, as defined by the two members 34, the contact arm 78 will be deflected, thus closing the pair of contacts 80 and operating the relay mechanism, thus causing the machine to cease its operation.

The purpose of making the bottom plate 60 of the various pockets removable, particularly where the upper row or tier of card receiving pockets is concerned, is to afford access to the lower card line therebeneath. As is sometimes the case, a card jam may occur and in such an instance, with permanent bottoms, little hand space would be afforded for remedying the condition. By means of the present pocket construction, the visibility of the lower card line is not impaired and the operator is readily able to determine the exact location along the card line where the source of trouble resulted in a card jam is situated. It is then merely necessary to remove the individual bottom plate 60, which is immediately above the source of the trouble, so that free access may be had to the cards on the lower card line.

While there have been shown and described and pointed out the fundamental novel features of the invention as applied to a preferred embodiment, it will be understood that various omissions and substitutions and changes in the form and details of the apparatus illustrated and in its operation may be made by those skilled in the art, without departing from the spirit of the invention. It is the intention, therefore, to be limited only as indicated by the scope of the following claims.

35. What is claimed is:

1. In a card pocket construction, a pair of partition members defining a partition wall, means for securing the upper ends of said members from a supporting surface at spaced points, 40 said partition members extending downwardly from the supporting surface in spaced relationship, a supporting bar for the lower ends of said partition members, means for supporting said bar from a supporting surface, there being a pair of bores formed transversely in said bar at spaced points therealong, the lower ends of each of said supporting members being turned laterally, a threaded cap screw extending through each of said bores and having its lower end passing through the laterally turned end of one of said partition members, and a shelf member disposed below said laterally turned end of each of said partition members and into which one of said cap screws is threadedly received, said shelf member extending forwardly of its respective partition member and providing a supporting surface thereon, said pair of partition members forming a dividing wall between adjacent card receiving pockets in a series thereof, said supporting surface being designed to receive thereon the rear edge of a removable pocket bottom plate for the pocket on the forward side of said partition wall and said supporting bar being designed to receive thereon the forward edge of another bottom plate for the pocket on the rear side of said partition wall.

2. In a multiple deck sorting machine having an upper card line and a lower card line, a vertically extending front plate and a vertically extending rear plate, a plurality of upper card supporting members extending across said plates in spaced relationship and defining the upper card line, a plurality of upper card supporting members extending between said plates and defining a lower card line, a multiple card receiv-

ing pocket construction including a plurality of adjacent card receiving pockets disposed above the lower card line and including a plurality of partition walls dividing the space between said plates above the lower card line into a plurality of adjacent card receiving pockets, the upper end of each of said partition walls being secured to the underneath side of a respective card supporting plate, means for supporting the lower edges of said partition walls from said rear plate, said rear plate and said upper card supports forming the sole supporting means for said partition walls, a removable bottom plate extending between the lower ends of each pair of adjacent partition walls, and frictional means for securing said bottom plates in position between said partition walls; said bottom plates closely overlying the lower card line of the sorting machine.

3. In a multiple deck sorting machine having a vertically extending front plate and a vertically extending rear plate, a plurality of upper card supports extending across said plates at the top thereof and defining an upper card line, a plurality of lower card supports extending across said plates in the medial regions thereof and defining a lower card line, the space existing between said plates above the lower card line defining a card receiving pocket region, a multiple pocket construction disposed within said region and comprising a plurality of partition walls dividing said space into adjacent card receiving pockets and each having their upper edges secured to one of said upper card supports, said partition walls projecting downwardly to points immediately below the lower card line, a plurality of rigid supporting bars, one for each partition wall, extending across the machine in parallelism and to which the lower ends of said partition walls are secured, means for securing said bars to and for supporting the same from the rear plate, means providing a forwardly extending shelf at the lower end of each partition wall, and a substantially flat removable bottom plate for each pocket having its rear edge region resting upon one of said shelves and having its front forward edge region resting upon the sup-

porting bar associated with the next adjacent partition wall forwardly of said shelf.

4. In a multiple deck sorting machine having a vertically extending front plate and a vertically extending rear plate, a plurality of upper card supports extending across said plates at the top thereof and defining an upper card line, a plurality of lower card supports extending across said plates in the medial regions thereof and defining a lower card line, the space existing between said plates above the lower card line defining a card receiving pocket region, a multiple pocket construction disposed within said region and comprising a plurality of partition walls dividing said space into adjacent card receiving pockets and each having their upper edges secured to one of said upper card supports, said partition walls projecting downwardly to points immediately below the lower card line, a plurality of rigid supporting bars, one for each partition wall, extending across the machine in parallelism and to which the lower ends of said partition walls are secured, means for securing said bars to and for supporting the same from the rear plate, means providing a forwardly extending shelf at the lower end of each partition wall, and a substantially flat removable bottom plate for each pocket having its rear edge region resting upon one of said shelves and having its front forward edge region resting upon the supporting bar associated with the next adjacent partition wall forwardly of said shelf, and a tongue formed on each bottom plate adjacent the forward edge thereof designed for latching engagement with the supporting bar upon which the forward edge region of said plate rests.
